UNITED STATES PATENT OFFICE

STERLING W. ALDERFER, OF AKRON, OHIO, ASSIGNOR TO THE GARL SIGNAL COMPANY,
OF AKRON, OHIO, A CORPORATION OF OHIO

NONINTERFERING ALARM BOX

Application filed October 8, 1927. Serial No. 224,889.

This invention relates to the art of electric signalling, particularly to systems of signalling used in fire alarm circuits, although it is not necessarily confined to that particular art, but may be employed for other purposes and in other capacities.

The particular object of the present invention is to design and construct an alarm system or an alarm box of the non-interfering type, that is, one in which a series of boxes or stations are arranged in series upon a single line, and in which mechanism is provided so that the transmission of a signal from one box or station on a line will not interfere with a signal which is being transmitted from another box. In alarm systems, if one box upon a line is "pulled" and the alarm is being transmitted, which consumes a period of time, owing to the necessity of repeating the box number, a second box on the same line may be pulled. In non-interfering alarm systems, to which this invention relates, the "pulling" of a second box will not interrupt or interfere with the transmission of the signal from the first box, but the alarm from the second box will be delayed until the first box completes its cycle, and the second box will then come into action to transmit its own signal without attention on the part of the person operating the second box, or interference by the first box.

Non-interfering systems have been known heretofore, but the systems as designed heretofore are quite complicated and are easily put out of order. The present invention is designed to simplify this type of system and to construct and perfect an accurate, mechanically operated, non-interfering system. As will be seen by the detailed description of the invention, each box is provided with mechanically operated mechanism to insure non-interference. The mechanism in the box is simple and cannot get out of order or deteriorate and become ineffective as with prior types of systems of this general nature. Other improvements over the constructions of the prior art and elements of novelty and usefulness will be apparent upon a further study of the invention as described herein.

It will be understood, however, that while

the drawings and description are quite detailed, the broad principles of the invention may be embodied in different forms and structures, and the claims are intended to cover such variations or modifications as may be fairly held to fall within their scope and within the true scope of the invention as set forth herein.

In the drawings, in which the present known and preferred form of the invention is shown:—

Figure 1 is a front elevation of the mechanism incorporated in a single box in a fire alarm system showing the front of the box where the non-interfering mechanism is located;

Figure 2 is a plan view of the parts shown in Figure 1;

Figure 3 is an enlarged section on the line 3—3 of Figure 1;

Figure 4 is an enlarged detail of the non-interfering mechanism, the box being in the position of rest;

Figure 5 is an enlarged detail of the pivot for the shunt lever; and

Figure 6 is a diagrammatic view showing the manner of connecting a series of the boxes in a line together with the connections at "headquarters".

The views show the complete self-contained mechanism which is mounted in a box, the casings and other fittings common to alarm boxes being omitted. Each unit is mounted upon a base plate 2 having a vertical face or wall 3, preferably of semicircular construction to fit the standard pole box used in municipalities. Upon the rear of the wall 3 is secured the usual clock mechanism 5 which houses the coil spring drum 6, adapted to be wound by the key 7 projecting outwardly of the plate and operating through pinions 8. A gear train 10 is operated from the spring, having the usual regulating and escapement mechanism, as is standard in all boxes of this type and need not be described in detail.

The last of the gear train is secured to a shaft 12 which projects through the face 3 and carries the code wheel 14, the outer periphery of which is notched or provided with teeth 15 to correspond with the number of the

box, these teeth being arranged in groups or sets of the numbers required for the particular system. The code wheel, shown in Figures 1 and 4, is intended for the box number 5 426, this number being repeated four times about the wheel, and runs in the direction of the arrow X. On the wheel, just prior to the first group of teeth is located an elevated blank sector 16, which provides a period in 10 the rotation of the wheel which may be described as a "feeling" period during which time the box is operated to determine whether or not another box in the same line is sending in an alarm. The operation of this portion 15 of the code wheel will be described more fully later.

The face of the code wheel is provided with a circular wall or flange 20 elevated above the wheel, this wall being continuous except in 20 the sector opposite the sector 16 and at a point lying within the first signalling group. As the wall approaches the sector 16 it is cut down, as shown, to provide a thin web 22 which terminates at the beginning of the 25 "feeling" sector. Immediately following this point is arranged a transfer device in the form of an inclined lifting cam 23 extending from the outer edge of the disk to the inner line of the flange 20, from which point the 30 wall is broken to provide a gap 24. Shortly thereafter the wall is cut away again to provide a second short gap 25 which is located at some point within the first signalling group.

35 On the face of the code wheel is mounted a sliding stop or block 30 cooperating with stop pins 69 to be later described, which is guided for movement radially of the wheel over pins 32 by slots 31, the block being 40 moved outwardly and held at its outer limit of movement by a leaf spring 34 received at its free end in a recess 35 on the block and anchored at its inner end to the face of the wheel as shown at 36. The outer end of the 45 block is provided with a hook 38 which lies closely adjacent the end of the web 22. The rear of the block is provided with a pin 39 which projects through a slot 40 in the code wheel 14 and lies within the path of a vertically movable plunger 42, by which it is to 50 be elevated. The plunger is guided at its upper end in a block 43 attached to the wall 3, and at its lower end in the base plate 2, being pivoted at its lower end to an operating lever 55 45, rocking in an angular bracket 46 secured to the underside of the plate 2. The outer end of the lever is provided with an operating knob 47 and the plunger is maintained at its lowermost point by a spring 50. When the 60 person operating the box pulls the knob 47 downwardly, the upward movement of the plunger releases the code wheel momentarily, sufficiently to allow the wheel to commence 65 its rotation under the influence of the clock

mechanism and to continue until it completes a single effective ringing cycle.

On the face plate 3 is mounted a shunt lever 55, this arm being pivoted on one side of the face plate upon a pin 56 and retained by a bolt 57 (Figure 5). The pin is secured in position by a bolt 58 passing through the plate 3. The arm is insulated from the plate by fiber washers and bushings 60. The bolt 58 serves as a binding post for a shunt wire 61 leading from a main binding post 62 in the base plate to a double electro-magnet 64 mounted in a bracket 65 in the upper portion of the face plate. Electrical connection from the pin 56 to the arm 55 is maintained through flexible wire 66 connecting the bolt 57 and the arm.

The arm 55 passes just below the wheel, at which point it is provided with an insulating bracket 68 from which projects a pin 69 adapted to ride within or outside of the wall 20. When the pin is riding upon the inside of the wall, the outer end of the shunt lever is in close relationship to the magnet 64, and the armature 70 carried by the lever and passing through an opening 71 in the face plate is attracted and held by the magnet, if it is energized. When the magnet is not energized, the shunt lever will fall, provided the pin 69 is opposite any of the gaps in the wall, until its outer end rests upon a stop pin 72 mounted on the top of a vessel providing a mercury bath 73 secured to the face plate. When the parts are at rest with the pin 66 outside the web 22, the armature is out of contact with the magnet and removed to such an extent that it cannot be attracted thereby. The lever 55 is provided with a pin 75 which dips in the mercury bath pot, making electrical contact therewith.

Starting with the parts at rest, as shown in Figure 4, the wheel is held from rotation by contact of the pin 69 with the hook 38 on the stop block 30. If the knob 47 be depressed, the plunger 42 will raise the catch or stop block and the wheel will be released, whereupon it immediately starts its rotation. The cam surface 23 elevates the pin and the shunt lever until the armature is brought in close contact with the magnet, where it is retained, if the current is flowing continuously through the magnet during the operation of the "feeling" sector 16 and until the pin 69 is within the wall 20. If the current through the magnet is interrupted while the pin 69 is passing over the gap 24, the pin will fall through the gap, but if the current is maintained, it will pass over the gap and the wheel will continue its rotation until stopped by the contact of the pin 69 with the catch 38.

The alarm is transmitted to the central office through the code lever 80 which is pivoted upon the wall plate at 81, being pressed upwardly by a coil spring 82 bearing against the underside of the lever and against a

bracket 83 in the wall plate. Immediately below the code wheel on the lever 80 is secured an insulating block 85 in which is mounted a pin 86, held in contact with the 5 rim of the code wheel and through which the teeth upon the wheel actuate the lever to make and break the alarm circuit and thereby transmit the alarm. The end of the code lever is provided with a pin 87 which 10 dips in the mercury pot 73, so that both contacts are made through a single pot. The advantage of making both contacts through a single pot lies in the fact that loss or removal of the mercury from the pot would immediately 15 show up at the central office or headquarters since the shunt circuit would remain open. If separate mercury pots were used, and that of the shunt circuit were intact and that of the alarm circuit were open, 20 the alarm box would appear to be operative at headquarters even though the box would not be capable of serving its purpose when an alarm was turned in.

Referring particularly to Figure 6, which 25 shows two boxes upon a circuit, the lower box A (No. 426) is shown sending in an alarm, while the upper box B (No. 425) is in its normal condition. The circuit passes from the battery 90, through the signalling 30 relay 91 at headquarters, and through a telephone set 92 to the main line 93 which is connected to binding post 94 on the box A. From the post 94 the line 95 passes to the mercury pot 73. At this point it is provided with two 35 paths, one of which is a shunt through the shunt lever 55 direct to the binding post 62 and thence to the line 96, if the lever 55 is lowered, and the pin 75 in the mercury pot. If the lever 55 is raised, the current passes 40 through the code lever 80 and line 97 to the solenoids 64 and out through the line 61 to the binding post 62, the circuit through this lever being made and broken by the rotation of the code wheel. Before the line 96 leaves 45 the box, it passes through a telephone post 98 with which a removable telephone jack 99 carried by the line man may be inserted in the circuit for communication with headquarters through telephone 100 located at that 50 point. The circuit then passes through a telegraph key 101 and into the box B, being connected to the binding post 94 on that box. The number of boxes in a single circuit may be increased to any practicable extent and 55 the telephone and telegraph devices may be used if desired.

Having described the construction of a single box, a detailed description of the operation of the circuits will explain the manner 60 in which the non-interfering system is rendered operative.

It will be observed that the box is normally 65 on a closed circuit from line 93 through post 94 to mercury cup 73, through shunt lever 55 to post 62 to which is connected line 96.

Assuming that the parts are as shown in Figure 6, a person desiring to send in an alarm through box A, opens the box and pulls down the knob 47, which raises the plunger 42 and through the pin 39 elevates the catch to release 70 the pin 69. The code wheel immediately starts its rotation and, as the pin 69 passes off the surface 22, the shunt lever 55, which is supported thereby in its elevated position, will drop until its outer end rests upon the 75 stop 72. The inclined cam track 23 then picks up the pin and elevates it with the shunt lever until the armature 70 is in contact with the solenoids 64. As the code wheel continues 80 its rotation, the sector 16 will depress the code lever 80 and the circuit will be established through the line 97 and the magnet which is energized and thereby retains the arm in its uppermost portion until the pin 69 has passed the gap 24 and is riding upon 85 the inner surface of the wall 20. The wheel then makes its complete revolution, sending in the alarm through the operation of the lever 55. At the end of the revolution, the pin 69 is caught by the block 30 and the wheel 90 is again locked in position.

If, however, an alarm is being sent in from another box on the line, the circuit will be interrupted by the operation of the shunt lever 55 in the other box, and the armature 95 will be released through the de-energizing of the magnet 64 and the pin 69 will fall through the gap 24, riding about on the outside of the wall 20 until it is again picked up by the cam 23. If the other alarm has been completed 100 during the idle revolution of the code wheel, the energizing of the magnet will take place and the wheel will continue its revolution with the pin inside the wall 20. If the other alarm is still being sent, the wheel will continue 105 its revolution until the pin 69 is finally caught and held in its uppermost portion, whereupon the wheel will revolve for a full active ringing cycle and then stop by contact of the pin and the catch 38. The magnet constitutes 110 a temporary detent for the shunt lever 55, which detent is releasable by current interruption from other boxes in the ringing circuit.

The gap 25 is provided as an additional 115 measure of precaution in case two alarms in the same line were turned in simultaneously, whereupon both boxes might operate to pass the pin over the gap 24, but due to different timing of the strokes of the several alarms, one of the boxes would be rendered ineffective by release of the pin 69 as it passes over the gap 25. It is extremely improbable that two boxes on the same line would be pulled 120 at close enough intervals so that the "feeling" 125 period allowed by the sector 16 would not operate, but in case such a condition did occur, it would be corrected at the point 25. The gap 25 is of such dimension and so placed that the shunt lever pin can pass through the 130

same only at a point opposite to a code wheel tooth on the same alarm device whereby the operation of the code lever on the same alarm device will not cause the device to idle.

5 It will be observed that while the box is at rest, as shown at B, or while the code wheel is rotating with the pin 69 outside the wall 20, the pin 75 on the shunt lever 55 is in the mercury pot and the current flows through 10 lever 55, so that while the code lever 80 is moved by the index wheel, the flow of current through the line is not interrupted and the signal from the other box will not be interfered with.

15 It will be noted that pins 75 and 87 are adjustable so that they can be accurately set to contact properly with the mercury in the pot 73, and that the pin 75 is slightly lower than the pin 87 so that when the box is not 20 in operation, current will always be assured through the shunt by means of the lever 55. It will also be noted both pins are located in a single pot so that the current through the shunt and through the ringing circuit is 25 completed through the single mercury pot.

The device which has been described affords an accurate and positively acting, non-interfering alarm box. In a circuit, as has been described, the sending of a signal from 30 one box will not be interfered with if another box is pulled while the first is ringing, but the second box will continue to operate idly until the first has completed its alarm, whereupon the second will then take 35 up the circuit and send in its alarm until completion.

Having explained the mechanism as embodied in the alarm box forming the subject of the invention, it is obvious that variations 40 and modifications may be made without departing from the invention. It is possible to utilize the principles of the invention in boxes and mechanisms specifically different, and such other devices are intended to be 45 covered within the fair scope of the appended claims.

What is claimed is:—

50 1. A non-interfering alarm box, comprising a main alarm circuit passing through the box and divided into parallel circuits within the box, one of the circuits being an alarm circuit including alarm mechanism and the other a shunt about said mechanism, a movable switch forming a part of the alarm circuit and a second movable switch forming a part of the shunt, said switches being independently operable, said alarm mechanism including a code wheel having formations thereon for operating the switches in the code circuit and shunt, means operable by making or breaking the code circuit to hold the shunt switch in or release it from its open position, and a single mercury pot in which the switches dip to complete the circuit.

55 2. A code wheel for the uses and purposes

set forth, comprising a portion with designating formations thereon, a wall upon the face of the wheel, an inclined cam from the outside of the wheel to the inner surface of the wall, the wall being provided with a gap adjacent the inner end of the cam, and a releasable catch located at the end of the wall.

70 3. A code wheel for the uses and purposes set forth, comprising a portion with designating formations thereon, a wall upon the face of the wheel, an inclined cam from the outside of the wheel to the inner surface of the wall, the wall being provided with a gap adjacent the inner end of the cam, and a releasable catch located at the end of the wall, 75 in combination with a switch having a portion which may ride upon the wall as the wheel is rotated.
